THREAD-CONTROLLING MECHANISM FOR
SEWING MACHINESPercival J. Anton, Elizabeth, N. J., assignor to
The Singer Manufacturing Company, Elizabeth, N. J., a corporation of New Jersey

Application January 11, 1936, Serial No. 58,639

3 Claims. (Cl. 112—241)

This invention relates to thread-controlling mechanism for sewing machines and more particularly to the overedge type of sewing machines as represented in patent No. 933,033, to A. Grieb and dated Aug. 31, 1909.

One of the objects of this invention is to provide an improved thread-controlling mechanism which will maintain the needle-thread taut so as to cause the needle-loop to lie closely around the blade of the looper and thus insure an even tension on the thread. Another object of the invention is to so reduce the size of the previously cast-off needle-loop that the looper will not enter the cast-off loop on its next loop-seizing movement. A still further object of the invention is to provide an improved thread controller which will gently pull the thread from the supply, with the result that a light tension may be placed on the thread thereby reducing the possibility of breaking the thread.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings:

Figure 1 is a front elevation of an over edge stitching machine embodying the invention, the work-plate being omitted to expose the mechanism below the same.

Figure 2 is a top plan view of the machine shown in Figure 1.

Figure 3 is a perspective view of a portion of the machine showing the stitch-forming and thread-controlling mechanism of the machine.

In the embodiment of the invention selected for illustration, 1 represents the base in which is journaled in suitable bearings the main shaft 2 provided with a needle-actuating ball crank 3. Carried by the base 1 is a bracket-arm 4 provided with a head 5 formed with lateral bearing bosses 6 in which is fitted the reciprocating needle-bar 7 carrying a needle 8. Fixed to the needle-bar 7 is a collar 9 having a laterally extending lug 10 connected by means of the link 11 with the forward end of the needle-bar actuating rock-lever 12 mounted upon the fulcrum-pin 13 arranged at an angle to the horizontal and journaled in the bearing bosses 14 and having a rearwardly extending crank-arm 15. The crank-arm 15 carries a ball 16 embraced by a strap

17 at the upper end of the pitman 18 having at its lower end a strap 19 embracing the ball-crank 3 on the main shaft 2. From the above it will be observed that the actuating lever 12 operates in a plane inclined upwardly and backwardly to the vertical.

As shown, the machine is provided with a primary thread-carrying looper 20 and a secondary thread-carrying looper 21. The needle operates through the usual needle-opening in the throat-plate 22 in cooperation with the primary looper 20 which enters the needle-thread loops beneath the throat-plate, and the secondary looper 21 which enters the primary looper loops and presents its own loops to the needle above the throat-plate. The above described mechanism is the same as that shown and described in the Grieb Patent No. 933,033, dated Aug. 31, 1909, to which reference may be had for a more detailed description.

In order to improve the mechanism for maintaining the needle-thread taut and to insure an even tension on the needle-thread so as to retain the needle-loops snugly about the blade of the primary looper, there is mounted on the bracket-arm 4 beneath the usual thread-guiding plate 24 of the tension device 25 a member 26 having two arms 27 and 28 each of which is provided with a stationary guiding eye 27' and 28', respectively. Adjustably mounted on the rock-lever 12 by the screws 29 and slots 30 is a flat-sided thread-controlling finger 31 which extends upwardly between the arms 27 and 28. The flat-sided thread-controlling finger 31 is arranged in a plane parallel to the plane of movement of the lever 12 and is formed with a suitable convex-shaped edge 32 which is adapted to engage the needle-thread between the stationary eyes 27' and 28'.

The lead of the needle-thread A is as follows: 40 from the supply through the apertures 24' in the guide-plate 24, then between the usual tension-disks of the tension 25, the stationary eyes 27' and 28', the guide 33 and thread-check 34, both of which are carried by the needle-bar 7, 45 and finally to the needle 8.

Assuming the parts of the machine to be in the position shown in Figure 1, the needle being in its highest position, when the machine is operated, the needle descends and the thread-engaging cam surface 32 of the thread-controlling finger 31 engages the needle-thread A between the stationary eyes 27' and 28' and moves it outwardly, the cam surface 32 being so shaped as to keep the thread under control at all times. 55

When the needle reaches its lowest position, the thread is engaged by the portion Z (Fig. 1) of the cam surface of the finger 31 and when the needle begins its ascent the thread-finger 31 moves to the position shown in Figure 3. This movement of the thread-controlling finger 31 is not sufficient to take up all of the slack in the needle-thread, and consequently the excess slack thread is thrown out in a loop which is seized, as shown in Fig. 3, by the beak of the primary looper 20. On further ascent of the needle the thread-controlling finger 31 takes up the slack in the thread and the needle-loop is maintained snugly about the blade of the primary looper 20. By maintaining the needle-thread snugly about the blade of the primary looper the needle-loop is reduced in size and consequently when the primary looper 20 is withdrawn from the needle-loop, this loop is too small to be accidentally seized, together with the needle-loop, by the primary looper on its succeeding needle-loop seizing movement.

The stitch is set on the upstroke of the needle and the cam-edge 32 is so shaped as to gradually pull the thread from the supply through the tension 25. The gradual pulling of the thread from the supply permits the tension placed on the thread to be reduced thus minimizing the possibility of breaking the thread.

From the foregoing description it will be obvious that the elements employed are susceptible of material variation. The privilege is therefore reserved of resorting to all such legitimate changes therein as may be fairly embodied within the spirit and scope of the appended claims.

Having thus set forth the nature of the invention, what I claim herein is:—

1. A sewing machine having, in combination, a base, an overhanging bracket-arm fixed to said base and terminating in a head, a reciprocatory needle-bar journaled in said head and carrying a needle, a looper cooperating with said needle to form stitches, a needle-bar actuating lever pivoted on said bracket-arm, means for actuating said lever, a member fixed to said bracket-arm and having two spaced parallel arms arranged in planes parallel to the plane of the bracket-arm, and a thread controlling finger fixed to said needle-bar actuating lever and having a thread engaging convex shaped edge, said thread controlling finger extending upwardly between the two spaced parallel arms of said member.

oted on said bracket-arm, means for actuating said lever, a member fixed to said bracket-arm and having two spaced parallel arms arranged in planes parallel to the plane of the bracket-arm, said arms being provided at their free ends with 5 thread-eyes arranged in a plane at right angles to the plane of the bracket-arm, and a thread-controlling finger fixed to said needle-bar actuating lever and extending upwardly between said arms, said thread-controlling finger having a 10 thread-engaging cam edge.

2. In a sewing machine in combination, a base, a bracket-arm fixed to said base and terminating in a head, a reciprocatory needle-bar journaled in said head and carrying a needle, a looper co-operating with said needle to form stitches, a needle-bar actuating lever pivoted to said bracket-arm at a point intermediate its ends, means for actuating said lever, a member carried by said bracket-arm and having two spaced parallel arms 20 each arm being provided with a thread-eye, and a thread controlling finger fixed to said needle-bar actuating lever at a point between the needle-bar and the pivot point of said lever, said finger extending upwardly between the arms of said 25 member and having a thread-engaging convex-shaped edge.

3. A sewing machine having, in combination, a base, an overhanging bracket arm fixed to said base and terminating in a head, a reciprocatory 30 needle-bar journaled in said head and carrying a needle, a looper cooperating with said needle to form stitches, a needle-bar actuating lever pivoted on said bracket-arm, means for actuating said lever, a member fixed to said bracket-arm 35 and having two spaced parallel arms arranged in planes parallel to the plane of the bracket-arm, and a thread controlling finger fixed to said needle-bar actuating lever and having a thread engaging convex shaped edge, said thread controlling finger extending upwardly between the two spaced parallel arms of said member.

PERCIVAL J. ANTON.
